UNITED STATES PATENT OFFICE

134,301

DESIGN FOR A COAT

Oscar Hauptman, New York, N. Y.

Application June 23, 1942, Serial No. 107,307

Term of patent 3½ years

To all whom it may concern:

Be it known that I, Oscar Hauptman, a citizen of the United States, residing in New York city, in the county of New York and State of New York, have invented a new, original, and ornamental Design for a Coat, of which the following is a specification, reference being had to the accompanying drawings, forming part thereof, in which—

Figure 3 is a perspective front view thereof showing the belt untied and the fur panel in an open position.

I claim:

The ornamental design for a coat, as shown.
OSCAR HAUPTMAN.
